UNITED STATES PATENT OFFICE.

MARTHA M. WHITE, OF CAMPBELL, CALIFORNIA, ASSIGNOR OF ONE-HALF
TO HARRIET HIHN, OF CAMPBELL, CALIFORNIA.

KNEE-PROTECTOR.

SPECIFICATION forming part of Letters Patent No. 727,243, dated May 5, 1903.

Application filed January 14, 1903. Serial No. 139,060. (No model.)

To all whom it may concern:

Be it known that I, MARTHA M. WHITE, a citizen of the United States, residing at Campbell, in the county of Santa Clara and State 5 of California, have invented certain new and useful Improvements in Knee - Protectors; and I do hereby declare the following to be a full, clear, and exact description of the invention, such as will enable others skilled in 10 the art to which it appertains to make and use the same.

This invention relates to nether garments, and is directed to improvements in knee-protectors designed more particularly for use in 15 connection with overalls.

The nature of the improvement will be readily comprehended, reference being had to the following detailed description and to the accompanying drawings, in which—

20 Figure 1 is a front elevation of an overalls equipped with knee-protectors embodying the invention. Fig. 2 is an enlarged front elevation of the knee-protector. Fig. 3 is a vertical sectional view on line 3 of Fig. 2. Fig. 4 25 is a perspective view of the pad.

Referring to the drawings by letter, A A denote overall-legs to the outer side at each knee portion of which is secured, preferably by stitching, a pocket B of the material of the 30 overalls or other suitable material, the back of the pocket being the overalls, as shown in Fig. 3.

C is a flap at the pocket-opening, said flap being stitched at its upper edge, and in its

closed position the flap is secured by a button 35 d on the pocket engaging a hole e in the flap, or, as shown in Fig. 1, the flap may be secured in closed position by glove-fasteners f f.

G is a preferably rectangular pad consisting of a cover and a filling g, said pad being 40 removably insertible in the pocket and held therein by the closed flap. The pockets are, as above stated, located at the knee portions of the overalls, and when the pads are inserted the knees are cushioned and protected 45 against injury.

While the wearer is engaged in work which does not require a kneeling position, the pads may be removed, and the pockets may serve as receptacles for tools, nails, and the like. 50

I claim as my invention—

A knee-protector for a nether garment consisting of a pocket secured to the garment at the knee portion thereof said pocket having an open upper end, a pocket-closing flap secured 55 to the garment at the upper open end of the pocket, means for fastening the flap in its closing position, and a pad consisting of a cover closed at all sides and containing a filling, said pad adapted for removable insertion 60 in said pocket and to be retained by said flap.

In testimony whereof I affix my signature in presence of two witnesses.

MARTHA M. WHITE.
